UNITED STATES PATENT OFFICE.

WILLIAM A. RUGGLES, OF SCHENECTADY, NEW YORK, ASSIGNOR TO GENERAL ELECTRIC COMPANY, A CORPORATION OF NEW YORK.

MEANS FOR PRODUCING HIGH VACUUMS.

Application filed November 27, 1925. Serial No. 71,542.

My present invention relates to means for producing and maintaining a vacuum in electric discharge devices.

In devices of this character, and especially 5 in such devices which employ heavy currents, the life of the discharge device depends on the maintenance of a substantially perfect vacuum. Since the forces which produce gassing in a discharge device are roughly 10 proportional to the power involved, any overload or starting transient is particularly likely to cause the evolution of some gas in the device. The gassing effect is cumulative, the first gassing probably being small 15 and unimportant. A small amount of gas, however, makes the discharge device even more susceptible to gassing from abnormal conditions so that the discharge device soon evolves gas continuously and vigorously. 20 At such a time the discharge device is unfit for further use and is usually destroyed.

It is an object of my invention to provide a particular means which may be employed in connection with electric discharge 25 devices to efficiently and quickly produce a vacuum therein either initially or when the discharge device has begun to emit gas. The means employed to effect this result comprises a bulb having a coiled filament which 30 may be heated to incandescence. Within the filament and spaced therefrom is mounted a perforated metal holder containing a magnesium covered calcium wire. When the filament is heated the alkaline earth metal is distilled on the surface of the bulb and absorbs whatever water vapor or other gases 35 may exist in the bulb or discharge device. If desired, the filament may be operated intermittently or constantly in order to maintain 40 the vacuum.

The novel features which I believe to be characteristic of my invention are set forth with particularity in the appended claims. My invention itself, however, both as to its 45 organization and method of operation will best be understood by reference to the following specification taken in connection with the accompanying drawing in which Fig. 1 shows a tube partly broken away and which 50 embodies the features of my invention; Fig. 2 shows a cross sectional view of the metal to be distilled and the holder therefor; Fig. 3 shows in elevation the metal wire to be distilled and the holder therefor before assembly; Fig. 4 shows my invention as applied

to an electron discharge device of the three-element type, although obviously tube 1 may be employed with any type of electron discharge device desired.

Referring to the drawing, I have indicated 60 at 1, a glass tube or bulb which is adapted to be connected to an electric discharge device 2 by a glass extension 3 or by any suitable means desired. The bulb 1 has a reentrant portion 4 which is provided with the usual 65 glass seal or press 5 through which extends Dumet lead-in wires 6. The portions of wire 6 within the tube 1 are made of nickel, and the ends of the nickel wires are connected to a spiral filamentary conductor 7 of refractory metal, such for example, as tungsten, or any suitable heater wire. Mounted on the lead-in wires 6 is a pair of nickel disks 8 which act as shields for the seal 5.

A third conductor 9 of Dumet and nickel 75 wire is mounted on the seal 5. A hollow nickel cylindrical member 10 is attached to one end of the conductor 9 by means of a pairs of extensions 11 which are permanently connected to the conductor 9 and cylinder 10 80 in any suitable manner as by welding. The hollow cylindrical member 10 is provided with extensions 12 and 13 which are adapted to be bent to a horizontal position to thereby close the ends of the cylindrical member. A 85 plurality of relatively small circular openings 14 are placed at substantially diametrically opposite points of the member 10. Within the member 10, an alkaline earth metal is placed, which in the present instance is a magnesium covered calcium wire 90 15, such as disclosed in my copending application Serial No. 80,322, filed January 9, 1926. Ordinarily, calcium oxidizes and, therefore, deteriorates so rapidly that it can 95 not easily be handled. By providing the calcium with a magnesium coating, however, I have found that the wire thus formed may be exposed to the atmosphere for several hours without producing any harmful effects.

In operation, whenever the tube 2 begins to emit gas, current is supplied to the filament 7. The calcium within the nickel cylinder 10 will then distil through the openings 105 14 in the side of the tube 10 and through the ends of the tube. The area of the receptacle 1 is relatively large, and since the distilled vapor travels in a straight line from the openings in the nickel container 10, practi- 110

- cally the entire inner surface of the receptacle 1 is quickly covered with a metallic calcium deposit which immediately absorbs any water vapor or other gases which may exist within 5 the receptacle 1. A large surface on which to deposit the alkaline earth metal is particularly desirable owing to the fact that the ability of the distilled metal to absorb gases depends on the amount of surface which may 10 be covered by the distilled metal. I have found the present arrangement of a relatively large receptacle with a perforated elongated cylindrical holder filled with an alkaline earth metal to be particularly efficient in quickly 15 producing and in maintaining a perfect vacuum.

If desired conductor 9 may extend through the glass seal 5 so that a potential may be applied thereto as well as to the filament 7. 20 In this manner tube 1 may act as a two-element rectifier having an anode 10 and a filamentary cathode 7.

While I have shown the receptacle 1 in combination with an electron discharge device 2, obviously the invention is not restricted to the combination shown. The device may be employed for maintaining a vacuum in a receptacle such as the tube 1 without reference to any other electric discharge device. 30 Various modifications of my invention will readily suggest themselves to persons skilled in the art without departing from the scope of my invention as set forth in the appended claims.

35 What I claim as new and desire to secure by Letters Patent of the United States, is:

1. In combination, a receptacle, an elongated metallic cylinder mounted within said receptacle, an alkaline earth metal mounted 40 in the cylinder, a heater wire surrounding the cylinder and spaced therefrom, means whereby current may be supplied to said heater wire to distil said alkaline earth metal, said cylinder being provided with openings so arranged that the distilled metal will cover the greater portion of the inner surface of said receptacle.

2. In combination, a vacuum device comprising a press, a pair of conductors extending 50 through said press, a coiled heater wire connected to said conductors, a supporting element mounted on said press, a hollow elongated receptacle having perforated sides mounted on said supporting member and

within said coiled heater wire, and an alkaline earth metal mounted within said hollow receptacle. 55

3. In combination, a receptacle, a coiled heater wire within the receptacle, a tubular metal container mounted within the coiled 60 heater wire and spaced therefrom, said container being provided with a series of openings extending longitudinally of said container, and an alkaline earth metal mounted within said container, and means whereby 65 current may be supplied to said heater wire to distil said alkaline earth metal upon the inner surface of said receptacle.

4. In combination, a receptacle, a coiled heater wire mounted within the receptacle, 70 an elongated integral metal container mounted within the receptacle, said container being provided with openings in the ends and sides thereof, an alkaline earth metal mounted within said container, and means whereby 75 current may be supplied to said heater wire to thereby distil said alkaline earth metal upon the inner surface of said receptacle.

5. In combination, a receptacle, means for absorbing gases within said receptacle, said 80 means comprising an integral tubular member provided with a series of openings extending longitudinally of said member, an alkaline earth metal mounted within the member, and means for heating the member 85 to vaporize said alkaline earth metal and thereby absorb gases within said receptacle.

6. In combination, a receptacle, means for absorbing gases within said receptacle, said 90 means comprising a container, a metal, adapted to be vaporized, mounted in the container, means including a filament spaced from the container and adapted to be heated to incandescence to vaporize the said metal, said container being provided with a plurality of 95 openings so arranged that the vaporized metal will be deposited upon the inner surface of the receptacle.

7. In combination, an electron discharge device comprising a container, a coiled filamentary cathode and an anode mounted in 100 said container, said anode comprising a hollow perforated cylindrical member mounted within the cathode, and an alkaline earth metal mounted in said cylindrical member. 105

In witness whereof, I have hereunto set my hand this 25th day of November, 1925.

WILLIAM A. RUGGLES.
